LIGHTNING ARRESTER AND PARTS
THEREFORJohn W. Kalb, Barberton, Ohio, assignor to The
Ohio Brass Company, Mansfield, Ohio, a corpo-
ration of New Jersey

Application October 5, 1951, Serial No. 249,910

15 Claims. (Cl. 175—30)

1

This invention relates to an improved lightning arrester. It includes an improved pressure-release construction and an improved arrangement of spark gap and valve blocks within the arrester housing.

When a lightning arrester is called upon to withstand currents and/or voltages beyond its capabilities the resulting current follow-up arc is prolonged or sustained sufficiently to raise the pressure of the gases within the housing to damage the housing. According to this invention the cover or sealing cap over one end of the housing of the arrester is provided with a thin easily ruptured diaphragm which gives way under the pressure of the generated gases. This frangible diaphragm is preferably of thin, soft metal such as copper and is dished or domed inwardly to prevent the flexing which would occur as the result of atmospheric changes and cause crystallization of the metal near the edge of the diaphragm were the diaphragm made perfectly flat. The diaphragm is applicable to arresters of this general design and is not limited to use on an arrester with spark gap and valve blocks arranged as in the accompanying drawings.

It is customary to provide an elongated housing of porcelain or other vitreous or insulating material for a lightning arrester and to locate spark gaps and valve resistor blocks longitudinally of the housing. The gaps are usually located at one end of the housing and the valve blocks at the other. According to this invention the gap is located at substantially the longitudinal center of the housing with some of the valve resistor blocks at one end of it and others at the opposite end of it.

There is a decided advantage in such an arrangement of the spark gap and valve blocks, and this is independent of the type of lightning arrester and is in no way dependent upon the use of a diaphragm or other pressure-release means.

When the porcelain of the arrester housing is dry its resistance is very high. The voltage drop over the outside surface of the porcelain housing approaches quite exactly the drop of the gap and valve blocks within the housing, because to a large extent the dry housing gets its voltage from the gap. However, when wet and dirty the outer surface of the housing becomes somewhat of a conductor and is reluctant to have its voltage changed by the effect of the spark gap and valve blocks within it. Any large voltage difference between the inside and outside of the arrester results in flow of current through the

2

capacity of the porcelain wall. Any current which flows inwardly through the wall causes an additional voltage drop across that part of the housing. This is conducted to ground through the impedance of the gap resistor elements and valve resistor blocks. Since the valve resistor blocks are of relatively very low impedance, they remain unaffected by this current flow.

10 However, with the spark gap at either the upper or the lower end of the housing, when the housing is wet and dirty the gap resistor elements located within the housing conduct more and more current as the distance from the line terminal increases due to their having to conduct the added current which enters through the wall of the housing. Since the resistance per unit length of the gap is uniform the voltage per spark gap unit must necessarily be greater, the greater the distance of the element from the line terminal.

When the gap is located at the longitudinal center of the housing the voltage differences between the gap and the outside of the housing are much less than when the gap is located toward one end of the housing or the other. Furthermore, the voltage differences are symmetrical with respect to the center of the gap, so that whatever the difference in voltage between the inside and outside of the housing, and whatever the flow of current through the housing, the distribution of the voltage and current is substantially symmetrical on the two ends of the gap. By reducing the difference in potential between the outside of the housing and the gap, and by making the current distribution more uniform, the arrester operates more efficiently and consistently than where there is a larger voltage differential between the exterior of the housing and the gap or the current flow is not as uniformly distributed.

45 A logical extension of this principle is to arrange small valve and gap elements alternately within the housing, thus even further improving voltage distribution. However, this arrangement involves certain disadvantages not involved by the structure of this invention. These disadvantages are:

50 1. The gap elements are less rigid than the valve blocks, and a column in which several valve blocks and several gaps alternate is free to bulge to one side or the other and there is danger of damaging the valve blocks as they strike the inner housing wall during shipping vibration. On the other hand the large surface contact

between two touching blocks prevents shifting between the blocks, and all blocks at each end of the housing are held in axial alignment, uniformly spaced from the inner wall of the housing, reducing the liability of damage during shipping. Dividing the valve blocks into two groups and supporting these at the respective ends of the housing, gives the most stable internal arrangement, less subject to damage than when all the blocks are together or they are divided into more than two groups.

2. Subdividing the gap into a plurality of units necessitates additional operations such as pre-testing of several instead of one unit.

The invention will be further described in connection with the accompanying drawings, in which—

Fig. 1 is a section through the lightning arrester;

Fig. 2 is a section on the line 2—2 of Fig. 1; and

Fig. 3 is a diagram illustrating differences in the flow of current through the housing of a conventional lightning arrester and the improved lightning arrester of this invention.

The cylindrical porcelain housing 1 is of conventional design. Spaced coacting indentations 3 in the circular plates 4 form spark gaps. In each plate indentations spaced downwardly alternate with indentations spaced upwardly, there being three of each type of indentation in each plate positioned in a circle about the longitudinal axis of the gap pile. Thus each plate forms three spark gaps with the plate above it and three spark gaps with the plate below it. The plates are spaced by the blocks 6 of insulating or high resistance material. The rod 7 passes through the central holes 8 in the plates. The construction of this type of gap is more fully explained in Pyk U. S. 2,324,108.

The plates and rod rest on the metal disc 10. The rod extends upwardly through the top spacer 11. The spring 13 with the conductor 14 presses the electrodes 4 toward one another, and maintains them in electrical contact with voltage sensitive valve blocks 15 located above and below the gaps. It also maintains these valve blocks in contact with the metal discs 16, and these in turn with the end closures of the housing.

The annular rubber gaskets 20 encircle the opening at each end of the housing. These are held in place by deformable metal closures 23 and 24 the edges of which are spun into grooves 26 in the sides of the housing, forming gastight joints between the housing and the metal closures. Metal end castings 23 are cup shaped. The inner surface 30 of the cup and the outer edges 31 of the metal closures 23 and 24 are covered with asphalt and the space between them is filled with a suitable cement 32. The annular rubber washer 33 prevents the cement from entering the space at the end of the housing.

The annular metal spring 35 in each end of the arrester maintains the correct pressure on gasket 20. The arrester is evacuated through the hole 37 in element 24 which is closed with the metal plug 38.

There is a domed diaphragm 45 of thin copper which is brazed or otherwise fastened in a gas-tight manner in the opening in the element 23. This opening is located in a depression surrounded by the ridge 47. The valve resistor elements are supported on this ridge by the angular support 48 which offers a substantially three-point support. The diaphragm is as thin as practicable. The lower the pressure at which it rup-

tures, the better its performance. It is preferably no more than several mils thick, for example five mils.

The diaphragm is of smaller diameter than the valve resistor blocks and is protected by them from direct contact with any electric arc which occurs over the surface of the valve resistor blocks in the event of the arrester failing to quench or arrest the arc. Thus rupture is a function of pressure only, and is predictable and not affected by arc temperature.

In the event of a prolonged arc and subsequent accumulation of gases under high pressure within the housing, the diaphragm 45 ruptures permitting the pent-up gases to escape. These rush down around the valve resistor blocks, through the open end of the support 48 and under it. An end opening is provided in casting 28 to permit the escape of these gases after passing through opening 36 in spring 35. To protect diaphragm 45 under normal operating conditions, the end opening is provided with a closure member, preferably a snap-on cover 50, held in place by fingers 51.

25 Although the arrester has been described in considerable detail, the domed diaphragm 45 with or without a closure member such as the snap-on cover 50 may be adapted for use in various types of conventional arresters.

30 The diagram in Fig. 3 illustrates the advantage of locating the spark gap at the center of the arrester housing with valve blocks on each side of it. Although the diagram compares the effect of such an arrangement with arranging the spark gap at the top of an arrester (near the line terminal) only, the advantage of this arrangement over other conventional arrangements, such as locating the spark gap at the bottom of an arrester (near the ground) for instance, will be apparent 35 from the discussion which follows.

35 Figure 3 illustrates, diagrammatically, a conventional arrangement at the left with the improved arrangement at the right. The spark gaps are illustrated by straight lines and the valve blocks by ovals. The scale between the two arrester arrangements indicates the gradation of voltage approached on the outside surface of the arresters from one end to the other after the arresters have become dirty and are wet. The figures inside each of the arresters show the voltage drop over the gaps under ideal conditions. In wet weather, particularly after the exteriors of the housings have become dirty, there is current flow through the housings as indicated by the arrows. With the improved arrangement, locating the spark gaps at the center of the housing and the valve blocks at the ends, the maximum voltage differential between the outside of the housing and the gap elements is not as great as

40 the maximum is with the conventional arrangements, only one of which is illustrated. Because of the lesser voltage differential, less current flows through the housing in which the spark gaps and valve blocks are arranged in the improved manner. The less the flow of current through the housing, the more uniform the amount of current flowing through the several gap resistors because as more and more current enters the arrester, as illustrated in connection with the conventional arrester, the gap resistors at the bottom of the arrester carry a greater amperage than those at the top. Current flow through the housing is generally objectionable because the amperage carried by the several gap resistors is made non-uniform, and the over-all

operation of the arrester less efficient. Maximum efficiency is approached by placing the spark gap at the center of the arrester, with the valve blocks at each end of it.

What I claim is:

1. A lightning arrester which includes a vertical cylindrical porcelain housing closed at the bottom by a metal casting, a snap-on cover in the center of the casting, a gasket around the ends of the opening through the housing and in contact with the respective ends of the housing, and a deformable metal element at each end of the housing which holds the respective gaskets in place, the edges of said respective metal elements being held in gas-tight contact with the housing, said metal element at the bottom of the housing resting on a spring held under compression between it and the casting, the metal element having an opening at its center in line with the axis of the housing with a depression about the opening and a ridge projecting upwardly around the depression, a thin circular copper diaphragm domed inwardly located in the depression and so thin that it will be punctured by the pressure of gases generated within the housing on prolonged arcing, at about the longitudinal center of the housing a plurality of metal electrodes forming a spark gap pile, valve resistor blocks at each end of the housing larger in diameter than the diaphragm, an electrically conducting spring member in the housing maintaining the elements of the spark gap pile and the valve resistor blocks in pressure contact with one another, and means on the ridge supporting the bottom valve block and spacing it above the ridge to permit gases to pass downwardly between the bottom valve block and the ridge and thence through the space occupied by the diaphragm when the diaphragm is punctured by pressure of the gases generated in the housing.

2. A lightning arrester which includes a vertical cylindrical porcelain housing closed at the bottom by a metal casting, a snap-on cover in the center of the casting, a resilient gasket around the bottom edge of the opening through the housing below which is a deformable metal element the edge of which is held in gas-tight contact with the housing so that said metal element encloses the bottom of the housing with the gasket pressed between it and the housing, said metal element resting on a spring held under compression between it and the casting, the metal element having an opening at the center in line with the axis of the housing with a depression about the opening and a ridge projecting upwardly around the depression, a thin copper diaphragm domed inwardly located in the depression and so thin that it will be punctured by the pressure of gases within the housing on prolonged arcing, and means supporting resistor elements above the diaphragm within the housing on the ridge which surrounds the depression in the metal element but with a space between the bottom of the resistor elements and the ridge for the passage of gases under the resistor elements and over the ridge into the space occupied by the diaphragm after it is punctured.

3. A lightning arrester which includes a vertical porcelain housing one end of which is closed by a metal element having in a hole in the center thereof a thin copper diaphragm in line with the bore of the housing, which diaphragm is adapted to be punctured by gas pressure generated within the housing due to a prolonged arc, and resistor elements which are supported in the

arrester by the metal element and spaced out of contact with the diaphragm so that when said gases are generated within the housing they may pass down through the housing and between the bottom resistor element and the support therefor and thence through the punctured diaphragm.

4. A lightning arrester which includes a cylindrical housing and a covering at one end the central portion of which is formed of thin material adapted to be easily ruptured by excessive pressure of gases generated within the housing due to a prolonged arc.

5. A lightning arrester which includes a cylindrical housing and a covering at one end having a thin copper diaphragm at the center adapted to be ruptured by excessive pressure of gases generated within the housing as a result of a sustained arc when the pressure has reached a pre-determined value.

6. A lightning arrester which includes a cylindrical housing and a metal covering at one end having at the center thereof an inwardly domed center of thin material adapted to be ruptured by excessive pressure of gases generated within the housing due to a prolonged arc.

7. A lightning arrester which includes a cylindrical housing and a metal covering at one end having an inwardly domed center of copper no more than several mils thick.

8. A lightning arrester which includes a vertical porcelain housing having resistor elements therein, a rubber-like gasket surrounding the bottom opening of the housing, and a gas-tight metal element directly under the gasket with its edge sealed in gas-tight relation with the exterior of the housing, the metal element including an internally domed copper diaphragm no more than several mils thick.

9. The lightning arrester of claim 8 in which there is a cover for the bottom of the housing, an opening in the cover and an outwardly releasable closure member therein.

10. The lightning arrester of claim 8 in which there is a metal casting over the bottom end of the housing below the domed diaphragm, an opening in the casting substantially concentric with the housing, and a snap-on cover in the opening.

11. A lightning arrester which includes spark-gap and valve-block resistor elements in a cylindrical housing, a closure at one end of the housing having concentric with the housing a diaphragm which is easily ruptured by the pressure of gases generated in the housing due to a sustained arc, and in that end of the housing over the diaphragm and separating it from the spark gap elements one of said valve-block resistor elements which is circular and larger in area than the diaphragm.

12. A lightning arrester which includes a cylindrical housing having an opening in the center of one end thereof, over the opening a substantially gastight diaphragm at least a portion of the part thereof which covers the opening being frangible and adapted to be ruptured by excessive pressure of gases within the housing, and means shielding the inner surface of the diaphragm from hot gases generated with the arrester.

13. A lightning arrester which comprises valve-block resistors and spark-gap elements in a housing of vitreous insulating material, closure means at each end of the housing joined to the housing in a gastight manner, at least one closure means provided with an opening and a separately formed

diaphragm of rupturable material positioned in said opening concentric with the housing, the diaphragm formed of a material dissimilar to that of the closure means and of less thickness than the associated closure means and rupturable when a predetermined gas pressure not to exceed the rupture pressure of the housing is formed in the housing as the result of a sustained arc, the edges of the diaphragm being joined to the adjacent edge of the opening in the closure means in a gastight manner, and protecting means adjacent the said one closure means of greater area than that of the diaphragm to prevent an arc from impinging upon the diaphragm.

14. A lightning arrester as set forth in claim 13 in which the protecting means comprises a valve-block which is positioned adjacent to but spaced from the diaphragm and is of greater diameter than that of the diaphragm whereby said protecting means overlaps the diaphragm and prevents any arc formed in the housing impinging upon the diaphragm.

15. A lightning arrester which includes a cylindrical housing with spark-gap and valve-block resistor elements therein, an opening in one end of the housing, a sheet metal cover over the opening with a hole therein substantially concentric with the axis of the housing and a diaphragm closing said hole and an inwardly extending ridge bent in said cover around said hole whereby the cover is strengthened, said spark-gap and valve-block resistor elements being supported on said ridge.
